INVENTOR:
Noah Hill

United States Patent Office.

NOAH HILL, OF LEAVENWORTH CITY, KANSAS.

Letters Patent No. 97,918, dated December 14, 1869.

IMPROVED RAILWAY-CAR COUPLING.

The Schedule referred to in these Letters Patent and making part of the same.

To all whom it may concern:

Be it known that I, NOAH HILL, of Leavenworth City, and Leavenworth county, in the State of Kansas, have invented new and useful Improvements in Car-Coupling; and I hereby declare that the following is a full and complete description of the construction and operation of the same, reference being had to the accompanying drawings, making part of this specification, in which—

Figure 1 is a top view;

Figure 2 is a side view, in part a longitudinal section; and

Figure 3 shows one part or section of the coupling, turned one-quarter over, thereby showing the position of the parts when out of place.

The main body of the coupling is made of either cast or wrought-metal, and attached to the car in the usual manner, so as to form a bunter or buffer; but as the mode of attachment forms no part of my invention, I have not shown such in my drawings.

The lower and main section A, represented by the same letter in all the figures, embraces the whole of the stem and the lower half of the mouth. It is perforated, as shown at B, for purposes hereinafter described.

C, in the several figures, represents the upper section of the mouth-piece, which is secured to the lower section by a hinge-joint, as shown at D, so that the mouth can be opened, as shown in fig. 3.

The mouth is ordinarily kept closed by means of a spring, E, fastened to the main body, just back of the hinge, but which will yield to any unusual pressure, and thus release the coupling.

The upper section of the mouth is excavated just behind the lip, as shown at F, in figs. 2 and 3, for the purpose of forming a catch, corresponding in position to the opening B, as is fully shown in fig. 2.

The coupling-bar G consists of a solid bar of wrought-metal, having a conical-shaped head upon both ends, as shown in figs. 2 and 3. When this head is inserted into the closed mouth, the spring E yields sufficiently to allow the upper section C to rise sufficiently to allow the head to enter the mouth, so

that the catch formed by the recess E and opening B will engage the head, and hold it fast, but still allowing sufficient play to admit of the oscillation of the cars.

I will now describe my device for uncoupling at pleasure. This consists of bent lever H, having its fulcrum at I, upon the side of the lower section A.

The short arm of the lever H extends downward and forward of its fulcrum I, and is there pivoted to the lower end of the connecting-bar K, the upper end of which is pivoted to mouth-piece C, as shown in fig. 2.

There also extends inwardly from the lower end of the lever H, an arm, L, which is bent at right angles, so as to enter the opening B in the lower section of the mouth.

By depressing or drawing back the lever H, the bar raises the outer end of the section C, so as to clear the head of the bar G, and, at the same time, the bent arm L, fig. 3, lifts the head from the catch formed by the opening B, and this operation releases the bar at one end, while it is securely held by the other, ready for coupling again, when required.

The head of the bar is flush on two sides with the neck, so that in the event of one car jumping the track, or to be thrown into an unnatural position, turned over on its side, or thrown down an embankment, the mouth is opened, as shown in fig. 2, and the car released.

I do not claim the construction of the dead-head, nor, broadly, devices for simultaneously opening jaws and lifting a connecting-bar; but

What I do claim, and desire to secure by Letters Patent, is—

The arrangement, with the jaws C D and spring E, of the lever H, connecting-bar K, and lifting-bar L, constructed as described, and arranged to operate in connection with the link G, as set forth.

NOAH HILL.
